SAFETY RAZOR

Arthur W. Thistlethwaite, Atchison, Kans.

Application February 9, 1933, Serial No. 655,968

3 Claims. (Cl. 30—12)

This invention relates to safety razors and more particularly to means for locking the face plate thereof against accidental rocking and turning movement after the cutting blade has been adjusted to give the desired shave.

Heretofore in the construction of safety razors and particularly safety razors of the Gillette type, considerable trouble has been experienced in preventing turning movement between the face plate and supporting handle and tilting or rocking of said face plate on the handle after the latter has been adjusted to give either a light or close shave and this turning or tilting movement of the face plate on the handle not only tends to change or vary the character of the shave for which the blade of the razor has been previously set but often results in cutting or otherwise lacerating the face of the user.

The object of the present invention is to overcome these objectionable features and to provide a safety razor the construction of which is such that after the razor has been once adjusted to give the desired shave, accidental turning or tilting of the face plate on the supporting handle and consequent injury to the face is positively prevented.

A further object is to provide a safety razor including a locking rod housed within the supporting handle and operable from one end thereof to engage the usual threaded stud on the face plate whereby to securely hold said face plate in adjusted position.

A further object is to provide means whereby the locking rod may be adjusted longitudinally to accommodate different styles of razors or supporting handles of different lengths.

A further object is to provide a locking device which may be readily applied to practically all well known types of safety razors without necessitating any material change therein or may be built into the razor during the manufacture thereof.

A still further object of the invention is generally to improve this class of devices so as to increase their utility, durability and efficiency.

In the accompanying drawing forming a part of this specification:

Figure 1 is a perspective view of a safety razor constructed in accordance with the present invention showing the different elements thereof detached or separated.

Figure 2 is a longitudinal sectional view of the razor with the parts assembled.

Figure 3 is an enlarged detail longitudinal sec-

tional view of the upper end of the locking rod and the adjacent end of the threaded stud.

Figure 4 is a longitudinal sectional view illustrating a modified form of the invention.

Similar numerals of reference indicated correspondingly parts in all the figures of the drawing.

The improved device forming the subject matter of the present invention may be applied to any standard or well known type of safety razor and by way of illustration is shown in connection with a safety razor of the Gillette type, in which 5 designates the arcuate cap or face plate, 6 the guard, and 7 a cutting blade clamped between the face plate and guard in the usual manner.

The face plate 5 is provided with the usual centering lugs 8 which extend through corresponding openings in the razor blade 7 and guard 6 and also with a centrally disposed depending threaded stud 9 for engagement with a correspondingly

threaded tubular operating handle 10. The upper part of the handle 10 is provided with a thickened portion 11 and said thickened portion is preferably threaded throughout its entire length, as indicated at 12. Disposed within the handle

10 is a longitudinally adjustable locking rod 13 having its intermediate portion spaced from the inner wall of the handle and being preferably smooth, and its opposite ends threaded at 14 and

15. Disposed at the lower end of the handle 10 is a finger piece or knob 16, the outer surface of

which is preferably knurled or roughened to facilitate turning of the same, said knob being provided with a reduced neck 17 fitting within the adjacent end of the handle and constituting a bearing for the locking rod. The lower end 15

of the locking rod is adjustably threaded in a socket 18 formed in the neck 17 and which extends

an appreciable distance within the knob 16 so that by rotating the rod 13 within the knob said

rod may be adjusted longitudinally to accommodate supporting handles of different lengths.

A nut 19 is preferably threaded on the end 15 of the locking rod and bears against the flat upper surface 20 of the neck 17 whereby after the rod 16

is adjusted, said rod may be securely held in adjusted position.

The upper end of the locking rod 13 is preferably concave, as indicated at 21, and fitted in the concave seat 21 is a correspondingly shaped strip

of Babbitt metal or soft solder 22 against which 50

the adjacent convex end 23 of the stud 9 bears

when the rod 13 is adjusted to lock the face plate against turning or tilting movement. This soft

metal packing provided a cushion or seat and not

only prevents undue wear on or injury to the parts

but also causes the parts to fit true. If desired, however, the soft metal seat 22 may be dispensed with and the end 23 of the stud may fit directly on the concave seat 21 of the locking rod.

5 Under ordinary conditions, the upper end of the locking rod will be spaced from the lower end of the stud 9 so as to permit free rotation of the handle 10 on the stud to effect proper adjustment of the cutting blade to give the desired shave; 10 that is to say, either a close or light shave. After the adjustment has been effected in this manner, the finger piece or knob 16 is rotated, which causes the concave end of the locking rod to bear against the adjacent end of the stud 9, thereby 15 locking the head of the razor, including the face plate, guard and cutting blade, against turning or rocking movement on the handle or turning movement of the handle with reference to the head. It will thus be seen that owing to the engagement of the locking rod with the stud 9, the 20 face plate 5 and its associated parts will be positively held against both turning and rocking movement so that the character of the cut of the razor blade will not be varied after the razor has been once adjusted, and liability of cutting or otherwise lacerating the face of the user during the shaving operation is positively prevented. By 25 loosening the nut 19 and rotating the locking rod within the socket 18, said rod may be adjusted longitudinally to accommodate handles of different lengths, it being understood, of course, that the socket 18 will be of sufficient length to permit of adjustment of the rod for this purpose.

The device shown in Figure 2 of the drawing is 30 designed for application to razors already in use and when the device is applied to razors during the manufacture thereof, the locking nut 19 may be dispensed with.

In Figure 4 of the drawing, there is illustrated 35 a modified form of the invention particularly adapted for the Cooper type of razor. In this form of the invention, the lower end of the handle is threaded at 24 and in place of the smooth bearing neck 17, exterior threads 25 are formed on the neck for engagement with the threads 24 so that by rotating the finger piece or knob 26, longitudinal movement of the locking rod 27 may be effected to cause the upper end thereof to engage the threaded lug 28 and hold the head of the 40 razor against accidental rotation relative to the supporting handle.

It will, of course, be understood that the handle may be of any desired length and shape and in certain types of razors in which the end of the threaded stud 9 is flat, the adjacent end of the locking rod 13 will be correspondingly flat instead of concave.

It will thus be seen that there is provided a 45 comparatively simple and inexpensive device which will positively lock the head of a safety razor and its associated parts against accidental turning and rocking movement when shaving and by means of which liability of cutting the face is reduced to a minimum.

Having thus described the invention, what I 50 claim is:

1. A safety razor including a guard, a coacting face plate for clamping a razor blade against

the guard and provided with a depending threaded stud, the lower end of which is convex, a tubular handle threaded on said stud, a finger piece having a threaded socket opening through one end thereof, a longitudinally adjustable locking rod disposed within the handle and having its upper end provided with a concave seat for engagement with the convex seat of the stud and its lower end threaded in the socket in the finger piece and normally spaced from the end 10 of said socket, said finger piece being adjustable longitudinally of the rod for varying the effective length of said rod when the parts are assembled and being formed with a shoulder for engaging the end of the handle and limiting movement of the finger piece and rod into the handle, and a nut threaded on the rod within the handle and engaging the adjacent end of the finger piece for holding the rod in different positions of 15 longitudinal adjustment. 20

2. A safety razor including a guard, a coacting face plate for clamping a razor blade against the guard and provided with a depending threaded stud, a handle threaded on said stud, a finger piece having a neck fitting within the handle and constituting a bearing and having an annular shoulder about its outer end, said finger piece and neck being provided with a threaded socket opening through said neck, a longitudinally adjustable locking rod threaded in said socket and having its lower end normally spaced from the bottom of the socket and its upper end adapted to engage the stud, said finger piece being adjustable longitudinally of the rod for varying the effective length thereof when the parts are assembled and the shoulder abutting the end of the handle, and a locking nut threaded on the rod within the handle and bearing against the neck for holding the rod in different positions 30 of adjustment. 35

3. A safety razor including a guard, a coacting face plate for clamping a razor blade against the guard and provided with a depending threaded stud, the lower end of which is convex, a tubular handle having a thickened portion at 45 one end interiorly threaded and engaging the threads on the stud, a locking rod disposed within the handle and having its opposite ends threaded, the upper end of the rod engaging the threads on the thickened portion of the handle, and having its terminal portion provided with a concave seat, a soft metal packing fitted to said concave seat, a finger piece having a threaded socket engaging the lower threaded end of the locking rod and adjustable longitudinally thereof 50 to vary the effective length of the rod when the parts are assembled, said finger piece being provided with a reduced neck fitting within the handle and constituting a bearing having a shoulder about its outer end to engage the end of the handle and limit movement of the neck and rod into the handle, and a locking nut threaded on the rod within the handle and adapted to engage the adjacent end of the neck at said bearing for holding the rod in adjusted position. 55 60 65
